UNITED STATES PATENT OFFICE.

GOTTHARD END, ARNOLD SCHLAEPFER, AND AUGUST ALTENBURGER, OF NEUHAUSEN, SWITZERLAND, ASSIGNORS TO THE FIRM: "SCHWEIZERISCHE INDUSTRIE-GESELLSCHAFT," OF NEUHAUSEN, SWITZERLAND.

APPARATUS FOR SHARPENING THE CUTTERS OF DRAWING-PISTONS SERVING FOR MANUFACTURING THE GROOVES OF BARRELS.

1,205,876.

Specification of Letters Patent. Patented Nov. 21, 1916.

Application filed October 25, 1915. Serial No. 57,839.

To all whom it may concern:

Be it known that we, GOTTHARD END, ARNOLD SCHLAEPFER, and AUGUST ALTENBURGER, citizens of the Republic of Switzerland, 5 all residing at Neuhausen, Canton of Schaffhausen, Switzerland, have invented certain new and useful Improvements in Apparatus for Sharpening the Cutters of Drawing-Pistons Serving for Manufacturing the Grooves of Barrels; and we do hereby declare the 10 following to be a full, clear, and exact description of the invention, such as will enable others skilled in the art to which it appertains to make and use the same, reference being had to the accompanying drawings, and to letters or figures of reference 15 marked thereon, which form a part of this specification.

The sharpening of the cutters of drawing 20 pistons for manufacturing the grooves of gun-barrels has been hitherto performed by hand, which operation required very skilled workmen. But even the greatest exercise of skill in this kind of work was not 25 sufficient to warrant a perfect exactness in the execution.

The object of the present invention is to 30 devise an apparatus adapted to perform mechanically the sharpening of the cutters of such drawing pistons, *i. e.* an apparatus adapted to sharpen the cutters in a fixed manner and without the necessity of changing the position of the cutters in the drawing piston, so that they do not have to be 35 taken out of the drawing piston. It is also of importance, that the piece, which has to be sharpened, is always fed in the proper manner into one of the several sharpening positions. According to the present invention 40 this is effected by means of levers and a spring arrangement.

Two embodiments of our invention are shown by way of example in the accompanying drawings, in which—

45 Figures 1-5 illustrate the first embodiment. Fig. 1 shows an elevation partly in section; Fig. 2 shows a plan view of Fig. 1 and Figs. 3-5 show on an enlarged scale an elevation, a plan view and a section, respectively, of the cutters and a part of the drawing piston. Figs. 6-11 illustrate the second embodiment; Fig. 6 shows a plan view; Fig. 7 shows a section on the line

A—B of Fig. 6; Fig. 8 shows a part of Fig. 6, partly on a horizontal section and Figs. 55 9-11 illustrate the sharpening device in different positions.

In the first embodiment of the invention the slide 2 rests on a base-plate 1 and is adjustable in the horizontal direction. To 60 this slide there are fixed two supports 3 and 4 carrying two sliding pistons 5 and 6. Each piston is provided with a bore for the insertion of the drawing piston 7, on which are fixed cutters 8 and 8'. The fixing of 65 the drawing piston is effected by means of two chucks 9 and 10. To the above mentioned base plate 1 there is screwed a carrier consisting of three parts 11, 12, 13. This carrier can be adjusted by means of three 70 shafts 11', 12', and 13' in three directions. On the uppermost part of this carrier there rests a bearing 14, in which rotates a grinding shaft 15. The front end of the grinding shaft 15 carries a small grinding disk 16 75 tapering toward its edge. In the middle of this shaft there is mounted a driving wheel 17 receiving its drive from a cord 18 (Figs. 1 and 2).

The small cutters 8 and 8' have the course 80 of a helical line and the upper small cutters 8' are arranged transversely with regard to the lower cutters 8'. The two small cutters 8 and 8' form each a single piece and they are adjustably mounted in the drawing piston (Figs. 3-5).

In order to grind the cutters 8 and 8' exactly in accordance with their pitch it is necessary to shift the grinding piston 7, while it is rotated, accordingly in an axial 90 direction. To this end there is provided on the sliding piston 5 a screw thread 19, the pitch of which corresponds to that of the small cutters 8 and 8' and by means of which the piston 5 engages the corresponding nut 95 20 mounted in the carrier 3. This nut 20, which is capable of rotating, and which has two notches cut into a flange 20' and lying diametrically one opposite another, can be held fast during the grinding operation by 100 means of a stop hook 22 engaging one of said notches, so that during the axial displacement of the drawing piston 7 there is imparted a rotation to this piston 7 and to the small cutters. For the purpose of adjusting 105 the slide 2 we provide a scale 23 (Fig. 2)

and this slide is kept in the proper position during the grinding operation by means of the two clamps 24 (Figs. 1 and 2).

For the purpose of sharpening the small cutters 8 and 8' the latter need not be taken out of the drawing piston, on the contrary the operator can leave these cutters in the piston, so that he can introduce them together with the drawing piston into the 10 sharpening apparatus. Upon the fixing or clamping of the drawing piston within the two pistons 5 and 6 the grinding disk 16 is brought into the proper position with regard to one of the small cutters 8 or 8'. As shown 15 in Fig. 4 the grinding disk is set in such a manner, that it forms an angle with the small cutters; this is, however, not necessary. The shaft 15 is then rotated and the drawing piston 7 is shifted to and fro in an axial 20 direction. Owing to the rotation imparted to this piston 7 by the screw thread 19 provided on the sliding piston 5 the cutter to be ground is moved past the grinding disk 16 exactly in accordance with the course of its 25 pitch and it is thus sharpened. The nut is then turned through an angle of 180°, whereupon the small cutter crossing the just sharpened one is sharpened in the same manner. By adjusting the slide 2 in the proper 30 manner with regard to the grinding disk 16 it is thus possible to sharpen in turn all four cutters, the latter being at first sharpened on one side and afterward on the other one.

By using the hereinbefore described 35 sharpening apparatus it is possible to attain a much more accurate shape of the cutters with regard to the cutting profile (roundness, sharp cutting edges and so on) than would be the case if the sharpening was carried out by hand.

It is evident, that the sharpening tool could be moved in accordance with the course 45 of the small cutters relatively to the stationary drawing piston or one of the two parts, i. e. the sharpening tool or the drawing piston, can carry out the axial movement while the other carries out the rotary movement.

According to the embodiment of the invention shown in Figs. 6-11, in which corresponding parts have the same reference 50 letters as in Figs. 1-5, there is screwed tightly to the base-plate 1 a guide for a slide 2. To the slide 2 is rigidly connected the supports 3 and 4, which carry the drawing piston 7 resting in the sliding pistons 5 and 6, said slide glides in the longitudinal direction within said guide. On the base-plate 1 there are further mounted two bearings 28^a and 24^a carrying the rod 25. Two springs 26 and 27 effect in combination with the projecting lug 28, a to and fro movement of the slide 2 either toward the right or the left, according as the projecting lug 28 engages the 60 recess 29 or 30. On the same slide 2 are 65 mounted two pairs of bearings 31 and 32.

On each of the corresponding shafts 33 and 34 are pivotally mounted two levers 35 and 36, 37 and 38, respectively. The two supports 39 and 40, which are rigidly connected to the base-plate 1 serve as a support for the 70 two adjustable stop screws 41 and 42. The heads of these screws have the shape of toothed wheels, so that these screws can be independently adjusted by means of the hand wheels 43 and 44 in combination with 75 the toothed wheels 45 and 46.

This apparatus works as follows: Let us assume, that there has to be ground at first the surface 47 of the small cutter. In this case the projecting lug 28 is brought into 80 engagement with the recess 29 (position shown in Fig. 6), so that the spring 27 moves the slide 2 toward the left, while the spring 26 is out of operation. The turned down lever 35 strikes against the stop screw 41 and 85 remains in this position till the surface 47 is ground. Hereupon the lever 35 is turned upward and the spring 27 pushes the slide farther till the lever 36 touches the stop screw 41. This lever corresponds with the surface 90 48 of the small cutter and said surface can therefore be ground. The projecting lug 28 is then inserted into the recess 30, so that the spring 26 moves the slide 2 toward the right. The levers 37 and 38, which are clapped 95 down, strike in the same manner against the stop screw 42, so that also the surfaces 49 and 50 of the small cutter can be ground.

What we claim is:

1. In an apparatus for sharpening the 100 cutters of drawing pistons serving for manufacturing the grooves of barrels, means for fixing the drawing piston together with its cutters, a sharpening tool, an adjustable carrier for the fixing means 105 of the drawing piston and means independent of the cutters for moving the drawing piston and the sharpening tool in a positive manner relatively to one another in accordance with the helical line shaped course of 110 the cutters, substantially as described and as illustrated.

2. In an apparatus for sharpening the 115 cutters of drawing pistons serving for manufacturing the grooves of barrels, two sliding chucks for fixing the drawing piston, said chucks lying in the same axis and being adjustably mounted in the axial direction, a sharpening tool arranged between the sliding chucks, a screw-thread on one of 120 these sliding chucks corresponding to the helical line shaped course of the cutters and a nut, in which lies said last mentioned sliding chuck, the nut being rotatably and adjustably mounted and capable of being brought into two positions at an angle of 180°, substantially as described and as illustrated.

3. In an apparatus for sharpening the cutters of drawing pistons serving for

manufacturing the grooves of barrels, a sharpening tool, means for fixing the drawing piston together with its cutters, means for moving the drawing piston and the sharpening tool in a positive manner relatively to one another in accordance with the helical line shaped course of the cutters and stops for determining the different grinding positions of the drawing piston with regard to the sharpening tool, substantially as described and as illustrated.

4. In an apparatus for sharpening the cutters of drawing pistons serving for manufacturing the grooves of barrels, a sharpening tool, means for fixing the drawing piston together with its cutters, means for moving the drawing piston and the sharpening tool in a positive manner relatively to one another in accordance with the helical line shaped course of the cutters, a movable carrier for the fixing means of the drawing piston, stopping levers provided on said carrier and fixed stops acting together with said levers to determine the different grinding positions of the drawing piston with regard to the sharpening tool, substantially as described and as illustrated.

5. In an apparatus for sharpening the cutters of drawing pistons serving for manufacturing the grooves of barrels, a sharpening tool, means for fixing the drawing piston together with its cutters, means for moving the drawing piston and the sharpening tool in a positive manner relatively to one another in accordance with the helical line shaped course of the cutters, a movable carrier for the fixing means of the drawing piston, reversible stop levers provided on said carrier, fixed stops working together with said stop levers to determine the different grinding positions of the drawing piston with regard to the sharpening tool and springs acting upon the carrier for the fixing means of the drawing piston to shift the drawing piston upon the reversal of a stop lever into the next grinding position, substantially as described and as illustrated.

6. In an apparatus for sharpening the cutters of drawing pistons serving for manufacturing the grooves of barrels, a sharpening tool, means for fixing the drawing piston together with its cutters, means for moving the drawing piston and the sharpening tool in a positive manner relatively to one another in accordance with the helical line shaped course of the cutters, a

movable carrier for the fixing means of the drawing piston, reversible stop levers provided on said carrier, stop screws acting together with said stop-levers to determine the different grinding positions of the drawing piston with regard to the sharpening tool and means for adjusting the stop screws, substantially as described and as illustrated.

7. In an apparatus for sharpening the cutters of drawing pistons serving for manufacturing the grooves of barrels, a sharpening tool, means for fixing the drawing piston together with its cutters, means for moving the drawing piston and the sharpening tool in a positive manner relatively to one another in accordance with the helical line shaped course of the cutters, a movable carrier for the fixing means of the drawing piston, reversible stop levers provided on said carrier, stop screws acting together with said stop-levers to determine the different grinding positions of the drawing piston with regard to the sharpening tool, toothed wheels provided on said stop screws and toothed wheels meshing with said first mentioned toothed wheels and mounted on rotatable and adjustable shafts, substantially as described and as illustrated.

8. In an apparatus for sharpening the cutters of drawing pistons serving for manufacturing the grooves of barrels, a sharpening tool, means for fixing the drawing piston together with its cutters, means for moving the drawing piston and the sharpening tool in a positive manner relatively to one another in accordance with the helical line shaped course of the cutters, a movable carrier for the fixing means of the drawing piston, stops for determining the different grinding positions of the cutting piston, a projecting lug provided on an axially adjustable shaft, springs provided on this shaft and arranged on both sides of the projecting lug, notches in the carrier into which said lug may be introduced while one of said springs is tensioned, substantially as described and as illustrated.

In testimony that we claim the foregoing as our invention we have signed our names in presence of two subscribing witnesses.
